UNITED STATES PATENT OFFICE.

AUGUSTUS ALLENDORF, OF HARVARD, ILLINOIS.

LIGHTNING-ARRESTER.

1,092,510.

Specification of Letters Patent.

Patented Apr. 7, 1914.

Application filed October 9, 1912. Serial No. 724,867.

To all whom it may concern:

Be it known that I, AUGUSTUS ALLENDORF, a citizen of the United States, residing at Harvard, in the county of McHenry and 5 State of Illinois, have invented certain new and useful Improvements in Lightning-Arresters, of which the following is a specification, reference being had to the accompanying drawings.

10 This invention pertains to new and useful improvements in combined lightning arresters and cut outs for telephones and the primary object of the invention is to provide an efficient instrument of this character 15 which, when it receives attention will operate to protect the telephone or telegraph instrument to which it is connected from injury by currents of dangerous forces without injury to itself, and which, when neglected, 20 will, nevertheless, be equally efficient in protecting the telephone or other instrument without further injury to itself than the burning out of one or more inexpensive fuses which may be readily and automatically replaced.

25 A further object of the present invention resides in a combined instrument of this character which, when the fuses have been burnt out, will automatically drop from the 30 arrester and by again operating the switch a new fuse will be substituted therefor and at the same time carbons will be cleaned, thereby automatically presenting the instrument again for use without the necessity of 35 repairment.

40 The invention has for a further object a simple, durable and efficient construction of an apparatus of this character, the parts of which may be cheaply manufactured, readily 45 assembled and installed, and which will require practically no attention to maintain in proper running order. And the invention also aims to generally improve this class of devices and to render them more useful and 50 commercially desirable.

55 With the above and other objects in view, the invention consists of the novel details of construction, combination, formation and arrangement of parts as will be hereinafter 60 more fully described and particularly pointed out in the appended claims.

65 In the accompanying drawings has been illustrated a simple and preferred form of the invention, it being, however, understood 70 that no limitation is necessarily made to the

precise structural details therein exhibited, but that the right is reserved to any changes, alterations, and modifications to which recourse may be had within the scope of the invention and without departing from the 60 spirit or sacrificing the efficiency of the same.

In the said drawings, Figure 1 is a vertical section embodying my invention. Fig. 2 is a vertical section through the casing illustrating the instrument in elevation. Fig. 3 65 is a transverse section taken on the line 3—3 of Fig. 1. Fig. 4 is a similar section taken on the line 4—4 of Fig. 1. Fig. 5 is a horizontal section taken through the casing illustrating the instrument in elevation. Fig. 6 70 is a detail perspective view. Fig. 7 is a vertical transverse section on the line 7—7 of Fig. 1. Fig. 8 is a vertical section embodying a slightly modified means for operating the instrument, and Fig. 9 is a detail elevation 75 of the same.

Reference now being had to the accompanying drawings wherein like and corresponding parts are designated by similar reference characters throughout the several 80 views, the numeral 1 designates an inner casing made of suitable insulating material being supported upon a bracket 2 and having a metal cover 3 therefor, whereby access may be gained to the interior of the casing 85 when desired. This casing is inclosed in an outer metal casing 4 being secured to the outer wall of a building and having openings 5 formed therein to permit the circulation of air therethrough.

90 Journaled within suitable bearings 6 carried by one wall of the inner casing 1, is a shaft 7 made of suitable insulating material and extending through an opening 8 formed in one of the side walls of the casing 1. 95 Keyed upon the shaft are a pair of spaced cylinders 9 and 10, respectively, each having formed in its periphery a pair of diametrically opposite recesses 11 and the recesses in one cylinder being in alinement 100 with the recesses in the opposite cylinder for a purpose as will be hereinafter more fully described. Supported by means of brackets 12 are a pair of vertically extending slides or chutes 13 each terminating in a substantially semi-circular hood 14 which rests over the upper periphery of each of the cylinders 9 and 10, respectively. These chutes are for the storage of a plurality of heat coils or fuses 15 being made by winding fine wire 110

around brass tubes and soldered with the ordinary fuse solder, so that when a strong current passes through the same, it will melt the fuse solder, thereby permitting the coils to contract together for a purpose which will be hereinafter obvious. The inner face of each of the cylinders 9 and 10 respectively, is provided with suitable conducting plates 16 which are connected to the line terminals, as will also be later described. Also carried by the shaft 7 and keyed thereupon are a pair of spaced carbon blocks 17 which are in constant contact with the plates 16 and separated from an intermediate ground carbon block 18 by means of suitable insulating plates 19. These insulating plates 19 are permanently fixed upon the base of the inner casing 1 and are provided with a pair of diametrically opposite segmental openings 20 which are adapted to register with the carbon blocks 17 when the telephone wires are in circuit with the line wires. A circular ring 21 encircles the outer periphery of the carbon block 18 being made of suitable conducting material, such as brass, and having formed therein a plurality of notches 21', being preferably four in number. A spring actuated pawl 22 is permanently secured to the rear wall of the inner casing 1 and is in constant contact with the said ring and adapted to rest within the said notches 21' to prevent the rotation of the shaft, this spring actuated pawl being of suitable conducting material and is connected to a ground wire 23. The said shaft 7 is provided adjacent each end thereof with cylindrical bores 24 through which extend circuit wires 25 and 26, respectively, the inner ends of which are connected to the plates 16. A ring 27 is also carried by the shaft 7 and the opposite end of the wire 26 is connected thereto whereas the opposite end of the wire 25 is connected with a suitable platinum contact 28 carried by one of the brackets 6. The contact 28 is connected to a line wire 29 leading to a telephone or other instrument whereas the other line wire 30 is connected to a suitable contact 31 which is in constant engagement with the ring 27.

It is obvious from the foregoing that as the shaft is rotated, the cylinders 9 and 10 respectively will in turn also be rotated, and when the recesses 11 formed therein come in alignment with the chutes 13 fuses 15 will obviously rest within each of the recesses and the outer face of each of the cylinders is provided with leaf springs 32 formed of suitable conducting material and the free ends thereof are adapted to rest upon one end of each of the fuses to retain the same within the recesses 11. Suitable binding posts 33 are carried by the rear wall in the casing 1 and have extending therefrom spring contacts 34 which are adapted to

rest upon the said springs 32 at intervals. Connected to these binding posts 33 in the usual manner are the main line wires 35.

To provide means for operating the shaft 7 from the exterior of the building, I permanently fix upon the said shaft a ratchet wheel 36 made of suitable insulating material and having notches 37 formed in the periphery thereof and being preferably four in number, as shown. Freely mounted upon the said shaft upon each side of the ratchet wheel is a pair of radially extending arms 38 which carry a spring actuated pawl 39, being adapted to engage the notches 37 of the ratchet wheel. These arms 38 are provided with an extension 40 to which is connected a chain 41, or similar flexible member, depending through an opening 42 formed within the casing whereby the said arms may be oscillated, and this extension 40 is also connected to one end of a coil spring 43 having its opposite end secured to a bracket 44 fixed upon the inner face of one wall of the casing 7.

It will be seen from the foregoing that pulling downwardly upon the chain 41 the arms 38 will be oscillated whereby the shaft, through the pawl and ratchet, as before described, will be operated step by step. During the rotation of this shaft, the drums 9 and 10 and also the carbon blocks will be rotated and upon a quarter rotation of the shaft, or when the fuses contained within the recesses 11 are at right angles to the base of the casing the connection between the main line wires and the telephone wires will be cut out, but upon another quarter turn of the shaft the fuses contained within the recesses will be in circuit as more clearly illustrated in Fig. 1 of the drawings. When the fuses contained within the lower recesses 11 are in circuit the recesses formed in the opposite sides of the cylinders will be in alignment with the chute so that a new fuse may rest therein and be presented for use upon the next half turn of the shaft. When the contact springs 34 rest upon the springs 32 carried by the said drums, the current will be permitted to pass through the said springs, then through the fuses carried within the lowermost recesses formed within the cylinders, thence to the plates 16 and subsequently through the wires 25 and 26 respectively, to the wires leading to the telephone or similar instrument. Should a strong current of electricity pass through the line wires when the instrument is in this position, it will enter the fuses 15 carried within the lowermost recesses of the cylinders, and if the current is strong enough it will burn the fuses and melt the solder whereby the fuse will contract in length, thereby releasing itself from the springs 32 and permitting the same to drop through the tapered openings 45 formed within the base portion of the inner

casing 1 and thereby opening the connection between the main line wires and the telephone wires. By rotating the shaft a quarter of a turn, the springs 32 will obviously 5 be out of contact with the platinum contacts 34 thereby cutting off the connection between the phone wires and the main line wires. Should a current be passed through the main line wires strong enough to burn out the 10 fuses, as before described, the shaft should be rotated until the new fuses, which rest within the recesses formed in the opposite sides of the cylinders, are in circuit and by rotating said shaft the carbon 17 will be 15 cleaned and the carbon dust will fall through the openings 45 of the inner casing.

From the foregoing I have illustrated whereby the instrument may be manually operated from the exterior of the building, 20 but to provide means for operating the same in the interior of the building, I provide a mechanism, as best illustrated in the modified form of the invention, as shown in Figs. 8 and 9 of the drawings. In this construction, I provide a similar instrument, as before described, but eliminate the pawl and ratchet attachment for rotating the shaft. Extending through the opening in the wall of the building is a tube 46 being made of 25 suitable insulating material and adapted to be permanently connected to the reduced end 47 of the shaft 7, as before described. A suitable dial 48 is secured by means of set screws or the like to the inner wall of the 30 building and has identification marks thereon to designate the position of the instrument. A switch button 49 is carried by the inner end of the tube 46 and has extending 35 therefrom a pointer 50 which is adapted to 40 register with the identification marks to announce the position of the switch.

What I claim is:—

1. A device of the character described comprising a rotatable drum, fuses carried 45 by said drum, means whereby said fuses will be automatically dropped from said drum when burnt out, and means for automatically replacing the burnt out fuses upon rotation of said drum, as and for the purpose 50 described.

2. In a cut out and lightning arrester for telephones, comprising a rotatable shaft, drums carried thereby, fuses carried by said drums, means for supporting said fuses 55 within said drums, line terminals in circuit with said fuses, and means whereby said fuses will be released when a strong current of electricity passes therethrough, substantially as described.

60 3. A device of the character described comprising a rotatable shaft, drums carried

by said shaft, fuses carried by said drums, means whereby said fuses will be automatically dropped from said drums when burnt out, and means for rotating said shaft whereby the fuses will be brought into circuit. 65

4. A combined lightning arrester and cut out for telephones comprising a shaft, carbons carried by said shaft, means for insulating the carbons from one another, drums 70 carried by the shaft, means for feeding fuses to said drums, means carried by the drums for holding the fuses, and means for replacing the burnt out fuses upon rotation of the drums, as and for the purpose described. 75

5. A combined lightning arrester and cut out comprising a shaft, means for supporting the shaft, carbons carried by said shaft, drums carried by said shaft, conducting wires connected with the carbons, conducting wires connected with the drums, fuses carried by the drums for forming electrical connections between the drums and carbons, and means for replacing the burnt out fuses, 80 as and for the purpose described. 85

6. A device of the character described comprising a rotatable shaft, drums carried by said shaft, fuses yieldingly held within said drums, means for feeding said fuses to said drums, telephone wires in contact adjacent the opposite ends of said shaft, contacts carried by said drums, line wires connecting said contacts with said telephone wires, line wires extending into said casing, means for rotating said shaft whereby said 90 line wires will be brought into circuit with said fuses, and means whereby the fuses when burnt out will be released from said drums. 95

7. In a combined lightning arrester and cut out for telephones, the combination of an insulated casing, of an insulated shaft journaled therein, contact plates carried by said shaft, means for connecting said contact plates with the telephone wires, drums 105 carried by said shaft, the outer periphery of said drums having recesses formed therein and diametrically opposite, means for delivering fuses to said recesses, and means for retaining fuses within said recesses, one 110 end of said fuses being in contact with said plates, line wires extending within said casing, and means for intermittently operating said shaft whereby said line wires will be brought in circuit with the fuses, substantially as described. 115

In testimony whereof I hereunto affix my signature in the presence of two witnesses.

AUGUSTUS ALLENDORF.
